(57) **CLAIM**

The ornamental design for an electric bicycle, as shown and described.

DESCRIPTION

FIG. 1 is a front and left side perspective view of an electric bicycle embodying our new design;

FIG. 2 is a rear and right side perspective view thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is a rear elevation view thereof;

FIG. 8 is a front elevation view thereof;

FIG. 9 is an enlarged and partial perspective view of selected portion 9 in FIG. 1;

FIG. 10 is an enlarged and partial perspective view of selected portion 10 in FIG. 1;

FIG. 11 is an enlarged and partial perspective view of selected portion 11 in FIG. 1;

FIG. 12 is an enlarged and partial perspective view of selected portion 12 in FIG. 1;

FIG. 13 is an enlarged and partial perspective view of selected portion 13 in FIG. 1;

FIG. 14 is an enlarged and partial perspective view of selected portion 14 in FIG. 2;

FIG. 15 is an enlarged and partial perspective view of selected portion 15 in FIG. 2; and,

FIG. 16 is an enlarged and partial perspective view of selected portion 16 in FIG. 2.

(Continued)

The broken lines shown in the drawings depict portions of the electric bicycle that form no part of the claimed design.
